Primary Examiner — Melanie H Tung(74) *Attorney, Agent, or Firm* — Morgan, Lewis & Bockius LLP(57) **CLAIM**

The ornamental design for a refrigerator with graphical user interface, as shown and described.

DESCRIPTION

FIG. 1 is a front, left side, perspective view of a refrigerator with graphical user interface showing our new design; FIG. 2 is a front view thereof; and,

FIG. 3 is an enlarged front view thereof, the graphical user interface is shown separately for clarity of illustration. The broken line showing of the refrigerator forms no part of the claimed design.
